CHARLES H. JOCKMUS, OF ANSONIA, CONNECTICUT.

DETONATING-FUSE SPRING.

1,189,574.

Specification of Letters Patent.

Patented July 4, 1916.

Application filed March 20, 1916. Serial No. 85,315.

To all whom it may concern:

Be it known that I, CHARLES H. JOCKMUS, a citizen of the United States, residing at Ansonia, county of New Haven, State of Connecticut, have invented an Improvement in Detonating-Fuse Springs, of which the following is a specification.

This invention relates to detonating base fuses for projectiles, more especially to minor caliber fuses, and has for its object to provide springs for this class of fuses, which shall be perfectly reliable and simple and inexpensive to produce, as they can be blanked out and formed from sheet metal with great rapidity by automatic machinery and the danger of loss from breakage is practically eliminated. With this and other objects in view, I have devised the novel fuse spring which I will now describe, referring to the accompanying drawing forming a part of this specification and using reference characters to indicate the several parts.

Figure 1 is a perspective view of my novel fuse spring ready for assembling; Fig. 2 an elevation corresponding therewith; Fig. 3 a section on the line 3—3 in Fig. 2, looking in the direction of the arrows; Fig. 4 a perspective view showing the manner in which the spring is blanked out and the half collars are formed, and Fig. 5 is a longitudinal section of a well-known type of standard fuse showing the application thereto of my novel spring.

10 denotes the fuse body, 11 the cap having threaded engagement therewith, 12 the nipple, 13 a primer thereon, 14 the firing pin, and 15 the spring as a whole. The spring comprises a ring 16 having arms 17 extending from opposite sides thereof and standing at a slightly acute angle thereto, and half collars 18 at the outer ends of the arms. The entire spring is blanked out from sheet metal of uniform thickness, for example, metal of .023 thickness. It is a requirement that the half collars be much heavier than the rings and arms are required to be.

I have found in practice that the best results are secured by using metal of approximately the thickness stated above for the ring and arms, and by making the half collars of double thickness, that is, by doubling the metal upon itself to form the half collars. I therefore blank out at the ends of the arms plates having a longitudinal dimension double the width required for the half col-

lars and of a transverse dimension corresponding with the length of the half collars, and doubling the metal inward upon itself to form a double thickness, after which the 60 half collars are shaped to the required curvature. The springs are made ready for use by bending the arms toward each other at a slightly acute angle to the plane of the ring, all of these operations being performed by automatic machinery and at a high rate of speed.

The firing pin is provided at its base with a head 19 and intermediate the head and point with an enlargement 20 to give 70 it additional weight. In the assembled position, the arms lie in grooves 21 in the enlargement and the half collars inclose the pin between the weight and the head.

Fuses of this class are inserted in the 75 bases of the projectiles and detonate on impact. The projectiles are often fired at the rate of 150 a minute, have a velocity of 2,000 feet per second or more, and are expected to pass through a 3/16-inch steel 80 plate and explode within six feet of the plate. The explosion is effected as follows: The centrifugal force of the projectile causes the arms to open so that the head of the firing pin may pass between the half collars. Upon impact, the velocity of the projectile is checked, and, the firing pin being loose therein, the blow of the firing pin upon the primer detonates it, and the flame, passing through holes in the cap, ignites the 85 explosion charge of the projectile.

The metal of the half collars is sufficiently heavy to retain the firing pin against the possibility of contact with the primer under the ordinary conditions of handling and 95 transportation, thus rendering the fuses perfectly safe under all ordinary conditions. The cap is provided with a circular shoulder which receives the ring, and the spring as a whole and with it the firing pin are 100 secured to the cap by closing the met 1 of the cap surrounding the shoulder over the ring. These details of construction are not illustrated in detail, as they are wholly immaterial so far as the present invention is 105 concerned, and fuses of this class are in common use.

Having thus described my invention, I claim:

1. A fuse spring of the character described, formed from sheet metal of uniform thickness and comprising a ring, arms ex-

- tending from opposite sides thereof and bent at an angle thereto, and half collars at the ends of the arms formed by folding the metal upon itself and curving to shape.
5. 2. A fuse spring of the character described, blanked out from sheet metal of uniform thickness and comprising a ring, arms extending from opposite sides thereof and bent at an angle thereto, and plates at 10 the outer ends of the arms which are folded inward upon themselves and curved to form half collars, substantially as described, for the purpose specified.
3. A fuse spring of the character de-
- scribed, blanked out from sheet metal of uniform thickness and comprising a ring, arms extending from opposite sides thereof and bent at an angle thereto, and half collars at the outer ends of the arms, said half collars being formed from plates, having a longitudinal dimension double the width required for the half collars and a transverse dimension corresponding with the length of the half collars, folded inward upon themselves. 25

In testimony whereof I affix my signature.

CHAS. H. JOCKMUS.
